UNITED STATES PATENT OFFICE

114,963

DESIGN FOR A PHOTOGRAPHIC BIRTH- STONE BRACELET

Theodore Payne, 4th, West Allenhurst, N. J.

Application April 4, 1939, Serial No. 84,039

Term of patent 14 years

To all whom it may concern:

Be it known that Theodore Payne, 4th, a citizen of the United States, residing at West Allenhurst, in the county of Monmouth and State of New Jersey, has invented a new, original, and ornamental Design for a Photographic Birthstone Bracelet, of which the following is a specification, reference being had to the accompanying drawing, forming part thereof, wherein:

Figure 1 is a top plan view of a bracelet showing my new design.

Figure 2 is a front elevation of the bracelet shown in Figure 1, and

Figure 3 is a fragmentary perspective view showing one of the units of the chain or bracelet involving the photographic link, the birthstone link and the connecting link between the same.

I claim:

The ornamental design for a photographic birthstone bracelet, as shown.

THEODORE PAYNE, 4TH.
